UNITED STATES PATENT OFFICE.

ROBERT WEISS, OF KINGERSHEIM, GERMANY.

APPARATUS FOR TREATING TEXTILE MATERIALS.

No. 829,188.

Specification of Letters Patent.

Patented Aug. 21, 1906.

Application filed October 2, 1901. Serial No. 77,275.

To all whom it may concern:

Be it known that I, ROBERT WEISS, chemist, a citizen of the Swiss Republic, and a resident of Kingersheim, Alsace, Germany, have 5 invented new and useful Improvements in Apparatus for Treating Textile Materials, of which the following is a full, clear, and exact specification.

My invention relates to apparatus for 10 treating—that is, dyeing, bleaching, and the like—textile materials, such as cotton and the like, with circulating superheated liquids, and especially to that class of such apparatus wherein such treatment is effected without causing deterioration of the textile material by the hot vapors. In order to effect 15 this result, the materials treated must be kept at all times completely immersed in the liquid, and this is attained by disposing the 20 liquid-supplying vessel wholly above the tank which contains the textile materials to be treated.

The object of my invention is to provide 25 an improved apparatus of this kind having a device for reversing the direction of circulation 30 of the liquid through the operating-tank without injuring in any case the above-given conditions of treatment.

In the accompanying drawings, which illustrate 35 an embodiment of the invention, Figure 1 is an elevation with some of the parts in vertical section; and Fig. 2 is a sectional view of the four-way cock, showing it turned to a position different from that seen in Fig. 1, where this cock is also shown in section.

In the drawings, 1 represents a closed tank for receiving the textile materials to be treated and called hereinafter the "operating-tank," 2 a closed vessel containing the supply 40 of liquid provided with the usual appurtenances (such as safety-valve, pressure-gage, filling-funnel) and the lower part of which is situated at a higher level than the upper part of the operating-tank 1, and 3 a rotating pump for maintaining the circulation 45 of the liquid of treatment.

The pump 3 is connected through its suction-pipe 4 with the lower part of the supply vessel 2 and through the pressure-pipe 5 to 50 the four-way cock 6, which, on the other

hand, is connected through a pipe 7 with the upper part of the operating-tank 1, through a pipe 8 with the lower part of the latter, and through a pipe 9 with the lower part of the supply vessel 2. The suction-pipe 4 of the 55 pump projects into the interior of the supply vessel 2 up to a level situated below the level of the liquid contained therein.

When the plug of the cock 6 occupies the position of Fig. 1, the circulation of the liquid 60 is as follows: The liquid passes from the supply vessel 2 through the pipes 4, 5, and 7 into the upper part of the operating-tank 1, leaves the latter on the lower part, and returns through the pipes 8 and 9 to the vessel 65 2. In the position of the plug of the cock 6 seen in Fig. 2 the liquid passes in the reverse direction through the operating-tank 1, being forced by the pump through 5 8 into the lower part of the operating-tank 1 and leaving 70 the latter on its upper part in order to return through 7 9 to the supply vessel 2. In both cases the pump forces by pressure the liquid through the textile materials in the operating-tank.

It will be seen that the textile materials are under all circumstances immersed in the liquid, as even on irregularities of the pump working a minimum level of the liquid will 75 be created in the supply vessel 2 by the projecting suction-pipe 4.

11 is a tube or pipe which in working may be supplied with steam for heating the liquid in the vessel 2. This pipe can also be supplied with cooling water, as it will be necessary for discharging the apparatus in order to then preserve the textile materials from coming into contact with hot vapors. 10 is a pressure-regulating air-chamber branched on the forcing-pipe 5 of the pump.

Having now described my invention, what I claim is—

An apparatus for the purpose specified, having a closed tank to receive the materials to be treated, a closed liquid-supplying vessel, the bottom of which is at a higher level than the top of the operating-tank, means 95 for superheating the circulating liquid, a pump for circulating said liquid, a pipe connecting the induction side of the pump with 100

the liquid-supplying vessel, above the bottom of this latter vessel, and means for connecting the eduction side of the pump with either end of the operating-tank at will, and
5 for simultaneously connecting the other end of said tank with the bottom of the liquid-supplying vessel.

In witness whereof I have hereunto signed my name, this 20th day of September, 1901, in the presence of two subscribing witnesses. ¹⁰
ROBERT WEISS.
